R. G. DU BOIS

GOLF CUP DEVICE

Filed May 28, 1919

INVENTOR

Rheal G. Don Dow

UNITED STATES PATENT OFFICE.

RHESA G. DUBoIS, OF EAST ORANGE, NEW JERSEY.

GOLF-CUP DEVICE.

Application filed May 28, 1919. Serial No. 300,484.

To all whom it may concern:

Be it known that I, RHESA G. DUBoIS, a citizen of the United States, and resident of East Orange, in the county of Essex 5 and State of New Jersey, have invented certain new and useful Improvements in Golf-Cup Devices, of which the following is a specification.

This invention relates to a device used in 10 the outdoor game of golf, and it consists in certain improvements in connection with the cup and flag device composing the marker of a putting green, all of which will be more fully described hereinafter and pointed out 15 in the claims.

The purposes of my invention are:

First. To dispense with the usual pointed flag-staff or pin and central socket for it thereby allowing the player to insert the 20 flag-staff thoughtlessly without the bother of finding the socket in the bottom of the cup as he would have to do with the ordinary flag pin.

Second. To keep the flag-staff upright 25 and thereby prevent it from leaning over against the turf rim of the hole and thereby mutilating the turf and destroying the symmetry of the rim as players and caddies so often do when hurriedly replacing the 30 flag-staff or pin.

Third. To prevent the caddy, when sighting 35 in the player, from damaging the grass around the hole by jabbing the point of the pin into the turf.

Fourth. To allow the player, after a shower, to bail water out of the hole by simply lifting the water out through the medium of the receptacle on the end of the flag-staff and in the same way clear the cup 40 of loose leaves, sand or dirt.

Fifth. To enable the player to lift his ball out of the cup without stooping, and

Sixth. To allow the flag-staff to stand 45 alone on the green without having to stab a hole in the latter thereby obviating the necessity of stooping to lift the removed flag from a prone position on the green.

In the accompanying drawings,

Figure 1 represents a side-elevation of my 50 invention wherein the flag member is shown in the act of being lifted out of the cup.

Figure 2 a transverse sectional view in which the flag-staff is shown in full lines, and

55 Figure 3 a top view of the flag-staff.

To accomplish the foregoing advantages

I secure the lower extremity of a flag-staff 1 to a telescoping cylindrical cup-shaped member 2 which fits loosely within a corresponding fixed cup 3 set in the ground 4 of a putting green 5. This cylindrical or tubular member 2 comprises a flat bottom 6 which rests upon the bottom 7 of fixed cup 3 and is provided with a substantially full-width upwardly extending skirt 13. The flag-staff is attached to the center of the bottom 6 of the inner telescoping cup 2 through the medium of an integral extension 8 and nut 9. A shoulder 10 rests on the top of and passes through a conical reinforcement 11 rising from the bottom 6 of cup 2. A recess 12 receives the nut 9 so that the latter will lie flush with the bottom of the cup and not project below to injure the turf when the flag-staff is out and the cup resting upon the putting green. To still further prevent injury to the grass and to facilitate the entrance of the flag-cup 2, I dull the lower circumferential corner 19 of the cup.

Fixed cup 3 is beveled at 14 around its upper exterior edge in order to bring its interior vertical wall flush with the interior earth wall or lip 15 of the hole 18, as seen more clearly in Figure 1, avoiding the formation of a bevel which might create a rimming action of the ball. 16 is any ordinary flag attached to the top of staff 1. A golf ball 17 is indicated by dotted lines as lying in the cup in Figures 2 and 3.

Briefly described the operation of the device is as follows:

The hole 18 in the putting green 5 is only $4\frac{1}{2}$ inches in diameter and must be marked by the flag such as 16 flying from the flag-staff 1 so that the player can accurately locate the goal at the distance from which the play is to be made. On hilly links the flag is essential to locate the position, not only of the hole, but of the green itself, and it therefore becomes a very important element. On approaching, if the ball should drop in the cup or hole and the player does not care to stoop over to pick it out of the cup 3, all he has to do is to lift the flag-staff 1 out with one hand and remove the ball 17 with the other hand. In case the cup should be filled with rain water the latter may be quickly removed by merely lifting the flag-staff and emptying the cup 2.

In southern climates, where sand greens are used instead of grass greens, the sand

surface is kept smooth by dragging a mat over it. That operation is often performed by a laborer twice a day in order to smooth out foot prints and depressions caused by 5 the point of the flag-staff while in the hands of the players and caddies. In dragging the green around the hole, the drag brushes sand and gravel into the cup and quickly fills the pin hole in the bottom, and the 10 work of inserting the hand into the cup and digging out the dirt to open the hole becomes such a nuisance that green keepers become careless and neglect it altogether. The result is that the pin hole stays plugged 15 most of the time, and players chuck the pin into the cup where it leans over against the lip and bevels the hole and destroys its symmetry. This beveling of the hole causes rimming and takes away much of the charm 20 of the game.

In the use of my invention the tendency of the flag-staff to lean over against the turf-edge or lip 15 of the hole, by reason of wind or improper replacing, will be checked by 25 the contact of the skirt 13 with the inner wall 20 of the fixed cup 3.

The replacing of the flag may be done with the greatest facility by simply sliding the flag cup 2 into the fixed cup 3 quickly 30 without precision. And when so placed, the flag-staff cannot tip over sidewise to chafe the surrounding turf-edge 15. When the flag is out, and while the players are putting, the broad bottom 6 of the cup when 35 coming in contact with the green will not injure it, and the preservation of the turf around the cup will be thus maintained and the necessity of frequently moving the cup from one part of the green to another is 40 obviated.

Although I have described and shown one form of carrying out my invention it is obvious that an infinite variety of others might be substituted without escaping the main 45 idea.

Having thus described my device what I claim as new and desire to secure by Letters Patent is:

1. In a golf cup flag device, the combination 50 with a lining for the hole of a putting green, of a cylindrically cup-shaped member forming a flag staff base and which removably fits in and telescopes with said lining.

2. A golf cup flag device, consisting of 55 the usual cylindrical member adapted to be sunk below the surface of the green, in combination with a flag-base and flag-staff, said base comprising a cylindrical cup closed at the bottom and open at the top and having a flag-staff centrally attached to the bottom of the cup.

3. A golf cup flag device, consisting of the usual cylindrical member adapted to be sunk below the surface of the green, in combination with a flag base and flag-staff, said base comprising a cylindrical cup closed at the bottom and open at the top and having a flag staff attached to and terminating at the bottom of the cup. 65

4. A golf cup flag device, consisting of the usual cylindrical member adapted to be sunk below the surface of the green, in combination with a flag staff secured at its lower end to the bottom of a cylindrical cup, said cup telescoping with the fixed cup and removably resting upon its bottom therein whereby the flag staff is removably retained in upright position and the cup forms a means for elevating foreign matter from the 80 fixed cylindrical member. 75

5. In a hole-marker, a flag-base consisting of a cylindrical cup open at the top to receive a ball and being arranged and adapted to loosely telescope with the cylindrical interior wall of the hole, in combination with a stem portion rising from the central lower portion of the cup. 85

6. In a golf hole marker, a cylindrical hole-lining adapted to remain in the ground, in combination with a cylindrical removable cup-member telescoping with the interior of the hole lining, and a flag staff attachment for lifting out the cup member. 90

7. In a golf hole marker, a flag device comprising an outer cup adapted to line the hole, in combination with an inner removable cup-shaped member loosely telescoping with the outer cup and a central flag staff attachment rising from the bottom of the 100 inner removable member. 95

8. In a golf hole-marker, a flag staff having its lower end centrally attached to the lower portion of a cylindrical cup which telescopes with the vertical wall of the hole in the green, and which is open at the top to receive a ball, whereby the cup and staff may be lifted bodily together out of the hole. 105

9. In a golf hole-marker, a flag staff having its lower end held in the lower central portion of a cylindrical cup adapted to enter a cylindrical hole in the ground, said cup being open at the top to receive a golf ball, and having a width relative to the hole slightly smaller than the latter and which permits the cup to slide vertically and freely in and out but will engage the interior vertical wall thereof whenever the cup is rocked latterly while within the hole, whereby the staff will be held clear of the lip of the hole. 110

Signed at East Orange, in the county of Essex and State of New Jersey, this 16th day of May, A. D. 1919.

RHESA G. DU BOIS.
